(57) CLAIM

The ornamental design for outerwear as shown and described.

DESCRIPTION

FIG. 1 is a right side front perspective view of outerwear showing my new design;

FIG. 2 is a front view thereof; and,

FIG. 3 is a left side front perspective view thereof.

The even-length broken lines within the shaded area represent stitching which forms part of the claimed design. The uneven-length broken lines immediately adjacent to and surrounding the shaded areas define the peripheral bounds of the claimed design and form no part thereof. The uneven-length broken lines depicting the remainder of the outerwear form no part of the claimed design.
